UNITED STATES PATENT OFFICE.

WILLIE HOLDSWORTH, OF PROVIDENCE, RHODE ISLAND.

FALLER BAR FOR GILL-DRAWING FRAMES.

Application filed September 9, 1926. Serial No. 134,501.

This invention relates to faller-bars for gill-drawing frames and particularly to improvements in the construction of their teeth or pins and the method of applying them to 5 and holding them in the bars.

A principal object of the invention is to provide a faller-bar having a novel and improved type of pin which may be more conveniently applied to the bar to reduce its 10 cost of manufacture.

Another object of the invention is to provide a faller-bar in which the pins are held in exact alignment and accurately spaced the proper distance apart.

15 Another object of the invention is to provide a faller-bar which is stronger and less liable to be bent or buckled in use, and in which the pins are held more rigidly.

Another object of the invention is to provide a faller-bar which is more convenient 20 to repair by replacing one or more of its pins without requiring the removal and replacement of all of the pins.

Further objects of the improvement are 25 set forth in the following specification which describes a preferred form of construction of the invention as illustrated by the accompanying drawings. In the drawings:

Fig. 1 is a side view of the improved 30 faller-bar illustrated with its central portion broken away;

Fig. 2 is an enlarged side view of an end portion of the bar, showing it partly in section to illustrate the method of securing the 35 pins therein;

Fig. 3 is a cross-sectional view of the bar taken on line 3—3 of Fig. 2;

Fig. 4 is a view similar to Fig. 2 showing a section of the bar before the pins are applied thereto;

Fig. 5 is a bottom plan view of the end section of bar shown in Fig. 4;

Fig. 6 is a perspective view of the novel 45 and improved form of pin as used in the bar;

Fig. 7 is a plan view of the gauge or fixture used in setting the pins in the bar; and

Fig. 8 illustrates the method of using the gauge in setting the pins in place in the bar.

50 The present improved faller embodies, in general, a bar having its main portion drilled with round holes and slotted on its under side, and a series of flat-sided needles having cylindrical shanks or body portions

inserted in the drilled holes in the bar and 55 held in place by means of solder run into the slot on its under side.

As illustrated in Fig. 1, the bar 2 may be of conventional form with enlarged end portions 3 which engage with the threads of 60 the gill-screws employed for traversing the bars in the gill-drawing frame. The main or bridge portion 4 of the bar which extends between the ends 3 is of narrower width and provided with a series of teeth or pins 5 65 projecting above its top. In the construction of faller-bars used for drawing silk and other fine fibers the pins are made relatively fine and set close together, whereas for coarser materials the pins are larger 70 and heavier. In order to attain the close spacing of the pins for fine work it has heretofore been the practice to make the pins flat-sided, or more or less spear-shaped, to provide sufficient strength to prevent them 75 from bending or breaking. With this type of flat pins the problem of setting and securing them in place in the bar has been a difficult one and previous to the present invention no satisfactory form of construction 80 has been devised for this purpose. The flat or oval shaped shank or butt of the pin obviously cannot be held rigidly in a round hole, so that usually pins of this type are set into a recess or slot on the side of the 85 bar and then soldered in place by flowing the solder over the pins. With this method of setting the pins in the bars it has been found extremely difficult to hold the pins in alignment and to space them accurately 90 along the top of the bar. With round pins, such as used on the heavier bars for coarse work, this condition does not obtain because the cylindrical shanks of the round pins may be driven into drilled holes in the bar 95 and held without solder or other additional means.

To overcome the difficulty in setting flat pins in the faller-bar I have devised an improved type of pin having a novel construction embodying a cylindrical shank or butt end and a flat-sided tapered portion forming the working part of the pin which projects from the top of the bar. This improved form of pin is illustrated in Fig. 6 as having a cylindrical shank 6 and an upper flat-sided tapered blade 7 more or less like the shape of a dagger or poniard. As shown

more particularly in Figs. 4 and 5, the bridge portion 4 of the faller 2 is drilled with a series of cylindrical holes 8 while the under part of the bar is scored or milled out with a rectangular slot 9. With this construction the cylindrical shanks 6 of the pins 5 may be rigidly held in the drilled holes 8, and after the pins have been properly positioned, solder or the equivalent is poured into the slot 9 to anchor the pins in place.

It is of course necessary that the pins be properly placed in the bar with their flat sides in opposed relation, and to provide for convenience and facility in setting the pins in this manner I make use of a fixture or gauge bar 10 as illustrated in Figs. 7 and 8 of the drawings. The bar 10 consists simply of a strip of metal, usually bronze or brass, of rectangular cross-section and of a length corresponding substantially with the length of the faller-bar. In the gauge bar or fixture 10 I provide a series of flat-sided holes 11 corresponding in size and shape to the blade portions 7 of the pins 5 adjacent the point where they merge into the cylindrical shanks 6. In filling the faller-bar 2 with the pins 5 the latter are picked up in the fingers either singly or in groups and their cylindrical shanks 6 inserted into the round holes 8 in the bridge portion 4 of the bar. The shanks 6 of the pins fit the holes 8 freely, but without play, and the pins will drop down into the bar until their widened blade portions strike against the top thereof. After the faller has been filled with pins throughout its length in this manner the gauge bar 10 is brought against the points of the pins 5 to enter them into the flattened holes 11 therein. Now as the gauge bar 10 is brought into place against the top of the faller-bar 2, in the position as shown in Fig. 8, the blades 7 of the pins 5 will accommodate themselves to the holes 11 in the bar 10. In other words, the flat blade portions 7 of the pins 5 in passing through the correspondingly-shaped holes 11 in the bar 10 will be turned or rotated to cause them to register in proper relation to each other, and also to maintain them in exact alinement with an accurate spacing between their blades. With the pins held in register and positively spaced and alined in this manner, the bar 2 and the gauge 10 are reversed in position as illustrated in Fig. 8 and solder is then poured into the slot or recess 9. When the solder has hardened the pins 5 will be fixedly anchored in place with their shanks 6 held rigidly and securely in the holes 8 of the bar.

With the above described construction the pins are held in the bar in exact alinement with accurate spacing therebetween as required to provide for the maximum efficiency of operation. In other words, the pins may

be set in the bar as accurately as round pins, while at the same time the novel form of the pins provides the advantageous features of flat pins. This accuracy of spacing and exactitude of alinement is most important to insure good work in processing the fibers in the drawing frame. In certain classes of drawing two series of bars are employed with the pins from one set of bars projecting upwardly and those from the other set pointing downwardly between the pins of the lower bars. Therefore, if the pins are not accurately spaced and held in true alinement the pins on the opposed bars will strike against one another, causing them to be bent or broken and thus interfering with the proper operation of the machine. Moreover, with the improved type of pin as herein illustrated the sides of the pins are arranged in substantially parallel relation so that the spacing between the pins is practically uniform at top and bottom. This provides that the fibers will not tend to ride up out of the pins. That is, the pins will comb through the fibers without tending to lift and force the material upward because the space between the pins is not tapered or narrowed away from their points.

It will thus be seen that with the present improvement I obtain all the advantages of the flat type of pin without the disadvantages and difficulties inherent to the setting of the latter in the bar. In fact, with the present improvement the setting of the pins is made especially convenient and easy to accomplish and a much improved construction of the complete bar is attained. This not only makes for more economical cost of manufacture in the first instance, but also renders the bar easier and cheaper to repair. For example, if one or more of the pins becomes bent or broken they may be readily driven out from the holes in the bar and replaced with new ones without removing the whole series of pins, as is necessary with the common type of bar previously described. With the old type of bar the solder must be melted out along the whole bar to release all of the pins, after which a new set of pins is placed in a "book" or fixture and held in place while solder is again poured into the recess of the bar. With the present improved arrangement the individual pins may be driven out of their holes, replaced with new pins, and the solder simply touched with a heated iron to anchor the new pins in place.

It will also be noted that with my improved faller the main portion of the bar is not cut away or weakened to any considerable extent. Instead of slotting or cutting away the cross section of the bar on one side thereof, as is the common practice, with my present improvement only a small section of the bar is cut away at the bottom to

form the slot 9 for the solder. The bar is therefore much stronger and is less liable to be bent or buckled in use in the drawing frame.

5 In general, therefore, my improved faller-bar is much more economical to manufacture and repair, and much more efficient in use for the reasons as hereinbefore explained.

10 While I have herein illustrated the improvement as embodied in a certain type of faller-bar and with a preferred construction of the elements thereof, it is to be understood that various modifications may be made in the form and arrangement of the parts of the 15 device without departing from the spirit or scope of the invention. Therefore, without limiting myself in this respect, I claim:

1. An improved faller-bar provided with a series of cylindrical holes, and a series of 20 pins formed with cylindrical shanks inserted in the holes in the bar and secured fixedly in place therein and having flat-sided blades projecting therefrom in opposite spaced relation.

25 2. An improved faller-bar having cylindrical holes spaced along its upper edge and a slot on its under side, and pins having flat-sided working portions with cylindrical shanks, the shanks of said pins being inserted in the holes in the bar and anchored in place by solder flowed into the slot thereof.

30 3. As a new article of manufacture, a pin for faller-bars constructed with a pointed flat-sided portion and a cylindrical shank 35 extending therefrom.

35 4. As a new article of manufacture, a pin for faller-bars constructed with a cylindri-

cal shank and an integral flattened blade projecting longitudinally therefrom.

5. An improved method of manufacturing 40 fallers for gill-drawing frames, consisting in providing a bar with cylindrical holes spaced along its top, providing pins having cylindrical shanks and flat-sided blades, setting the pins in the bar by inserting their shanks in the holes thereof, and finally soldering the pins in place in their holes.

6. An improved method of manufacturing 45 fallers for gill-drawing frames, consisting in providing a bar having cylindrical holes 50 spaced along its top and a slot on its under side, providing pins having cylindrical shanks with flat-sided blades projecting therefrom, inserting the shanks of the pins in the holes in the bar, and flowing solder 55 into the slot in the bar to anchor the pins in place.

7. An improved method of manufacturing 60 fallers for gill-drawing frames, consisting in providing a bar having cylindrical holes spaced along its top, providing pins with flat-sided blades and cylindrical shanks, inserting the shanks of the pins in the holes in the bar, providing a fixture having flat-sided 65 holes corresponding to the shape of the blades of the pins, placing the fixture along the bar with the blades of the pins inserted through the holes thereof whereby to bring the pins into register with their flat sides in opposed relation, and finally applying solder or the like to the bar to anchor the pins 70 therein.

In testimony whereof I affix my signature.

WILLIE HOLDSWORTH.
